(57) **CLAIM**

The ornamental design for a watering wand, as shown and described.

DESCRIPTION

FIG. 1 is a top perspective view of a watering wand according to our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line shown represents portions of an adjustable watering nozzle and form no part of the claimed design.

The jagged broken lines are break lines. The appearance of any portion of the article between the break lines forms no part of the claimed design.

Conventional shading is illustrated for purposes of highlighting the line drawings, but forms no part of the claimed design.
